WILLIAM J. MILLER, OF SWISSVALE, PENNSYLVANIA

METHOD OF AND APPARATUS FOR AUTOMATICALLY RESHAPING AND DECORATING
WARE IN THE MANUFACTURE OF POTTERY

Application filed June 9, 1928. Serial No. 284,129.

This invention relates to a method of and apparatus for automatically applying additional material to, and reshaping and decorating pottery ware and contemplates the provision of a method and machine whereby the ware, preferably while in or on the mold and in a plastic condition and prior to the drying operation, may be subjected to what is termed in the pottery art as the slip-glazing operation or have additional material applied thereto and/or reshaped for decorative as well as utility purposes, the apparatus being also adapted for embellishment of the ware subsequent to the drying operation and is so constructed as to permit the application thereto of any number of attachments and different shapes of cams for applying the required design or embellishment and reshaping the ware as desired, the cams as well as other working parts of the apparatus being adjustable both while in operation and at rest, so as to facilitate accurate timing of the machine and measurement of the charges of additional material and positioning and variation of movement of the said parts while performing their respective functions.

Numerous other objects and advantages of the improved method and apparatus will become apparent in view of the following description and claims, to be considered in connection with the drawings, wherein:

Figure 1 is a fragmentary view in section and side elevation of apparatus which may be adopted in carrying out the method;

Fig. 1^a is an enlarged detail view of cams;

Fig. 2 is a fragmentary view in end elevation of the structure shown in Fig. 1;

Fig. 3 is a sectional plan view taken on the line 3—3, Fig. 1;

Fig. 4 is an enlarged view, principally in transverse vertical section, of parts taken from the apparatus to show the same more clearly;

Fig. 5 is an enlarged detail view of an adjustment structure;

Fig. 6 is a section taken on the line 6—6, Fig. 5;

Fig. 7 is an enlarged detail view in side elevation of a cam-mounting structure;

Fig. 8 is a section taken on the line 8—8, Fig. 7;

Fig. 9 is a view similar to Fig. 7 of a modification in structure;

Fig. 10 is a section taken on the line 10—10, Fig. 9;

Figs. 11 and 12 are detail views in section and elevation of a preferred form of valve structure and actuating cams;

Fig. 13 is a detail view in transverse vertical section of a charge-measuring and delivering device;

Figs. 14 to 18, inclusive, are enlarged fragmentary detail views in section and elevation of attachments;

Fig. 19 is an enlarged fragmentary detail view in side elevation of a modified form of attachment-actuating mechanism; and

Fig. 20 is a diagrammatic representation of parts of the apparatus in operation.

The additional material above referred to may be glaze, slip in a fluid or semi-fluid state such as engobe, clay in a more or less plastic state and of the same or a different color relatively to the ware, powdered, granular or fluid coloring or decorating material, and analogous decorative and utility mediums.

The apparatus in general is shown as being disposed to operate on the ware subsequent to the jiggering operation and prior to being passed through a drier, the molds on which the ware is formed being carried on recessed trays such as those disclosed in my copending application Serial No. 269,273, filed April 11, 1928, the trays being mounted in series in a conveyor, the construction and operation of which may be rendered more clear by referring to my copending application Serial No. 202,629, filed June 30, 1927. However, the ware may be treated at any stage of the fabricating operation and the molds may be disposed in position either manually or automatically, the present invention not being limited in this respect.

The numeral 5 generally designates a base supporting frame provided with tracks 6, the molds, indicated at A, being carried on trays 7, the latter being provided with projecting trunnions 7^a having grooved rollers 100

7^b thereon by which said trays are mounted in series in a flexible conveyor 8, the rollers having movement on and being guided by said tracks while the conveyor moves adjacent thereto, as shown in plan view in Fig. 3. 5 Supplemental frame units 9 are adjustably secured or clamped on cross bars 10, which in turn may be secured to, or form part of the frame 5, said frame units serving to support the chuck assembly which in the present instance comprises telescoping spindles 11 and 12 in spline-sliding engagement, the spindles 11 having bearing at their lower extremities in the frame units or castings 9 and the spindles 12 terminating in chucks 13. The lower portions of the spindles 12 are grooved or necked to receive the one extremity of cross forks 14, the opposite extremities of said forks being adjustably connected as by nuts 15 to pitmen 16, which have vertical slidable bearing in the frame units or castings 9. Levers 17 are pivotally connected at one extremity to the pitmen 16 and at their opposite extremities said levers are adjustably 20 and pivotally supported from the frame units 9, the pivotal connection being illustrated in detail in Figs. 5 and 6.

Referring to Figs. 5 and 6, the assembly preferably comprises a pivot or journal block 18, which is journaled in a longitudinally slotted portion of the lever or member to be pivoted or fulcrumed, indicated at L, and bored and threaded for insertion of an adjusting and retaining screw 19, said block 30 being also mounted to shift or slide through adjustment of screw 19 in a longitudinally slotted portion of a block or analogous member 20, the journal or bearing portion of block 18 being headed and the side walls of 35 the longitudinally slotted portion of lever L 40 formed with a retaining track or groove 21 for said head. Block 20 is adjustably secured to the supporting bracket or casting 22 of the assembly as by screw bolts 23 and 45 24 and positioning pin 25, the casting or bracket 22 being arcuately slotted as at 26 where the bolt 23 extends therethrough and a plurality of positioning holes 27 provided 50 in the bracket 22 for pin 25. By loosening bolts 23 and 24, pin 25 may be adjusted in any of said holes to definitely locate or spot 55 the angular position of block 20 relatively to the bracket or casting 22 and lever L, while screw bolt 23 may be adjusted in slot 26 to accomplish the same result independent of pin 25 and intermediate of holes 29. Adjusting screw 19 is journaled in end plates 20^a, which are secured to block 20, said screw being provided with a thrust or bearing collar 60 or set nut 28 and adjusting crank or handle 29. It will be seen that by turning screw 19, journal block 18 may be shifted in the guideway provided therefor and thus shift the pivotal or fulcrum point of lever L and vary 65 the throw of said lever or the extent of re-

ciprocation thereof from a stationary point and while in operation and while the driving and pivotal connection subsists. By adjusting the angle of block 20 and/or shifting the block 18, various advantageous adjustments 70 may be obtained. For instance, the extent of reciprocation of lever L may be varied without varying the lowermost point of reciprocation, or the intermediate point of reciprocation may be maintained constant 75 while at the same time varying the extent of reciprocation, or the lowermost point of reciprocation may be varied to a greater or less extent than the uppermost point of reciprocation, and vice versa, or the altitude of 80 reciprocation varied.

The foregoing assembly as a whole may in turn be adjustably supported by a turn-buckle or analogous member 30, threaded at opposite extremities in brackets 31 and 32, said turn-buckle being also adjustable to raise and lower the pivotal or fulcrum point of lever L, and to provide for both vertical and lateral adjustment independent of the turn-buckle, or as an alternate method of supporting the 90 assembly where the space available may not be sufficient to accommodate the turn-buckle assembly, the bracket or casting 22 and bracket 31 or other supporting member are slotted as at 33 and 34, to receive securing bolts 35. 95 By loosening bolts 35, the assembly as a whole may be adjusted both vertically and laterally.

Figs. 7, 8, 9 and 10 show a cam-mounting structure which may be adopted with a view to permitting change in the phase of motion 100 of the parts primarily actuated by the cams to which said structure may be applied while said parts are in operation and while the driving connection subsists. To illustrate, a cam is shown applied to a shaft s, which is formed with an annular threaded groove 36, said groove being located under the hub 37 of the cam in Figs. 7 and 8, the hub being formed with a bracket portion 37^a which may be bored to form a bearing housing for 110 an adjusting and set screw 38, the latter being formed with, or having secured thereon a gear or gear head 39, the one extremity of the screw housing or bore being enlarged to receive said gear and internally threaded to 115 receive an externally threaded retaining plug or nut 40. The hub and cam may be provided with a guide bore or slot extending at right angles to the screw 38, said bore or slot being adapted to receive a rack 41, in mesh 120 with gear 39, said rack being suitably secured at one extremity to a collar 42 provided with an annular groove 43, the collar 42 having a sliding fit on shaft s. A stationary adjusting screw 44 may be mounted in a suitable stationary supporting bracket or supported from any other adjacent stationary 125 part of the frame of the apparatus, the one extremity of said screw being provided with a lug or analogous member 45, adapted to ride 130

in the groove 43 of collar 42. The threads of annular groove 36 and screw 38 are preferably of the irreversible or single-thread type, to prevent angular displacement of the 5 cam due to work imposed thereon. It will be readily understood that by adjusting screw 44, the rack 41 in mesh with gear 39 will cause screw 38 to turn and thereby change or adjust the angular position of the cam 10 relatively to shaft 8, and this adjustment may be made while the driving connection subsists and while the shaft is in motion from a stationary point, the extent and position of adjustment being visible.

15 Figs. 9 and 10 show a modification in structure relatively to Figs. 7 and 8, to adapt the phase-changing adjustment structure to a smaller space and smaller or different types of cams. In this instance the screw 38 is 20 inserted directly in the cam, the latter being formed with a bore for this purpose, said bore terminating in an enlarged slot or recess 46. The teeth of gear 39 in this instance may be of such depth or extent as will permit said 25 teeth to project radially beyond the side walls of the cam. In assembling, the screw 38 may be inserted in the bore and the gear 39 in the slot 46 and the said bolt threaded into said gear and secured as by a countersunk screw 30 47. An adjusting segment 48, see Fig. 12, formed on one extremity of a rocking lever 49, the latter having a balancing or weighted head 50, may be used as a contact member for adjusting purposes, said lever being shown 35 mounted on a bracket shaft 51 formed with a longitudinal groove 52, a screw 53 being threaded through the lever 49 and projecting into said groove, said lever being thus limited in its rocking movement by screw 50 contacting with the side walls of groove 52. The 40 weighted head 50 of lever 49 serves to normally maintain the segment out of range of the projecting teeth of gear 39 or out of the radial path of said gear. To adjust the cam, the lever may simply be rocked inwardly to bring the segment 48 within the radius of the 45 projecting teeth of gear 39 as the cam rotates, this adjustment being reversed by sliding the said lever along its supporting shaft 51 and 50 engaging the teeth of gear 39 on the opposite side of the cam. Thus the operator may readily gauge the extent of adjustment, as at each rotation of the shaft and cam, the segment contacts with and imparts a definite degree of rotation to screw 38, so that the operator may be guided by the number of times the segment contacts with said screw in determining the extent to which he adjusts the angular position of the cam.

55 Reverting to Fig. 1, the levers 17 are provided with cam rollers 17^a adapted to contact with cams 54, preferably adjustably mounted as in Figs. 7 and 8 on a shaft 55, which may be of sufficient transverse extent as to accommodate the number of units employed and

have bearing at opposite sides of the stationary frame of the apparatus.

The casting of the frame units 9 is suitably bored to provide housings for the lower extremities of the spindles 11, the latter being 70 formed with annular bearing grooves and the housings may also be formed with annular grooves in registration therewith to receive bearings or, as shown in the present instance, bored to receive bearing pins 56 which also 75 serve to prevent longitudinal displacement of the spindles 11. The frame units 9 are formed with bracket portions 57, levers 58, formed at one extremity with gear sectors 58^a, being pivotally secured, preferably as in Figs. 80 5 and 6, to said bracket portions as at 59, arcuate slots 60 being formed in the lower enlarged portions of levers 58 and the bracket portions 57 being provided with studs or pins adapted to be received in said slots, to prevent longitudinal displacement of said levers. The gear sectors 58^a are adapted to mesh with pinion gears 61, adjustably secured on the lower extremities of the spindles 11, and the levers 58 are provided with cam rollers 62, 90 adapted to contact with cams 63, preferably adjustably mounted as in Figs. 7 and 8 on a shaft 64, which may also be of such transverse extent as to accommodate the number of units 95 employed and have bearing at opposite sides of the frame of the apparatus. It will be seen that the cams 63 serve to actuate levers 58 and impart intermittent rotation to the chucks 13, and these cams as well as the chuck-reciprocating cams 54 may be contoured to suit the work to be performed, as will hereinafter appear. The levers 58 are retracted by springs 58^b, which are secured at opposite extremities, respectively, to the 100 frame units 9 and levers 58.

105 Referring now to the upper portion of Fig. 1, the various units are supported from a platform or top plate 5^a, which is adjustably secured to and supported by side frame members or rails 5^b, the latter in turn being supported by columns or uprights 5^c, see Fig. 3, forming part of the main stationary frame of the apparatus. Guide posts 65 are adjustably secured as by nuts 65' to the platform or top plate 5^a, the upper extremities of said posts being threaded and extending through enlarged openings in said plate, these posts 65 being adapted to guide and support supplemental frame units generally indicated by the reference numeral 66, the lower ends of said posts being formed with stop heads 67, which in some instances support the frame units 66 when in their lowermost position and act as a stop for said units. The lower portion 110 of each frame unit 66 is formed with a transverse dove-tail groove, indicated by dotted lines at 68, a bar 69 being mounted to slide horizontally in said groove, said bar being formed with a bracket portion at one extremity to receive an adjusting screw 70. A le- 115 120 125 130

ver 71 is pivoted at its lower extremity to the bar 69 and at its upper extremity adjustably pivoted preferably as in Figs. 5 and 6 to a bracket portion or extension of the frame unit 66 as at 72. The upper transverse portion of the frame unit 66 is formed with a further dove-tail groove, also indicated in dotted lines, for slidably supporting a bar 73 in a horizontal plane, said bar terminating at 13 the left as viewed in Fig. 1 a suitable distance from the end of the said groove, thus providing a seat for a compression spring 74, adjustable through the medium of a screw 75, the bar 73 being adjustably maintained 15 under longitudinal pressure by said screw and spring. A suitable cam-contacting member or bracket 76 is secured to the bar 73, and to connect the bracket 76 and lever 71 in readily adjustable association, a turn-buckle 23 77 is pivotally secured to said bracket and lever, a plurality of securing holes being provided in lever 71 and bracket 76, so that the turn-buckle may be adjustably mounted thereon and adjusted at varying elevations 25 to adjust the throw of lever 71. A cam 78, see Fig. 1^a, is adjustably mounted, preferably as in Figs. 9 and 10, on a shaft 79, said cam being adapted to contact with bracket 76 to 30 impart horizontal movement to the bar 69 and such devices as may be secured thereto or supported thereby.

Each supplemental frame unit 66 is formed with a further dove-tail groove, to receive a bar 80, shown in edge elevation in Fig. 2, a further cam-contacting bracket 81 being secured on said bar and the latter being adapted to work against a spring 82, adjustable by screw 83, in a manner substantially similar to the bar 73. The bar 80 has horizontal 40 sliding movement imparted thereto by a cam 84, see Fig. 1^a, also adjustably secured as in Figs. 9 and 10 on the shaft 79, the latter preferably being of such transverse extent as will accommodate the number of units employed 45 and having bearing at opposite sides of the main stationary frame of the apparatus.

To impart vertical movement to the frame unit 66, a lever 85 is pivotally and adjustably secured at one extremity to the frame unit 66, the latter being formed with a bracket or ear 86, adapted to receive a pivot bolt 87 mounted on one extremity of said lever and adjustably secured as by set nuts or analogous means, and at its opposite extremity said lever 85 is pivotally and adjustably supported as in Figs. 5 and 6 from a bracket 88, which may form part of or be secured to the platform or plate 5^a, the pivot point of lever 85 being indicated at 89. The lever 85 is provided with a cam roller adapted to contact with a cam 90, shown in Fig. 1^a, said cam also being secured on the shaft 79 preferably as in Figs. 9 and 10 and whereby its angular position may be adjusted while the apparatus 50 is in operation.

It will be seen that the cams 78, 84 and 90 serve to impart lateral or horizontal movement to the bars 69, 73 and 80 and vertical or reciprocatory movement to the frame unit 66, and it is obvious that these cams as well as 70 other cams herein illustrated may be given such contours or shapes as will serve to produce the required movements in accordance with the work involved.

A decorating and shaping head assembly 75 and actuating mechanism therefor, partly shown enlarged in Fig. 4, is supported from the bar 69 and also from a bracket 91, the latter being suitably secured to the platform or plate 5^a, said assembly as 80 shown in Figs. 1 and 4 comprising a head generally indicated at 92, the latter in turn comprising a clay-contacting portion or facing 93, preferably of porous material such as plaster or bisque, said facing being removable and replaceably secured to a block 94 as by a ring clamp 95, said block and ring being provided with cooperating lugs or ears 96 adapted to receive securing bolts 97. The facing 93 is preferably chambered as at 98 90 and provided with removable and replaceable treating and decorating members 99, the latter being adjustably mounted and adapted to serve various functions, such for instance as nozzles to convey a treating and 95 decorating medium to the clay charge or ware and/or dies for forming or applying incrustations, indentations, projections or other configurations in or on the ware. The block 94 is threaded on a tool holder 100 and suitably 100 secured as by a pin or screw 101, said sleeve 100 being adapted to receive and have bearing in a further block 102, a gear 103 being secured on the upper extremity of the sleeve 100 as by a countersunk screw or analogous 105 means.

The upper annular portion of the holder 100 is formed with a flange 104, see Fig. 16, the interior of the sleeve providing an orifice or well 105 terminating at its upper extremity in a hopper 106, and at its lower extremity opening into the mold or ware-receiving portion or cavity of the facing 93. In assembling, the gear may first be applied on the holder 100 and secured and said holder then passed through the block 102 and threaded into block 94 and secured by pin 101. The block 94 and holder 100 are bored, to provide passageways or ducts 107 and 108 leading into the chambers 98, the block 102 being formed with annular grooves 107^a and 108^a and also bored as at 107^b and 108^b, the passageways or ducts 107 and 108 and bores 107^b and 108^b registering with said grooves, thus providing a 125 means for conveying a suitable fluid or other medium to the chambers 98 through the block 102, holder 100 and block 94. The bores 107^b and 108^b are provided with nipples 109 and 110 for connection of suitable hose or 130

other flexible members leading to a control valve, to be described.

It may also be desired to heat the facing 93, in which event suitable coils 111 may be disposed in the chambers 98, these coils being supplied with electric current in any well known manner, as by providing the block 94 with commutators 112 and 113 insulated therefrom and the block 102 with a brush-supporting bracket 114, brushes 115 and 116 being mounted on said bracket and adjustable to contact with said commutators. Each coil is grounded to the block and the latter in turn provided with a ground contact member as at 117, a ground wire being connected to said member. It is preferred to control each coil independently so as to provide selective heating means for the facing 93.

20 The gear 103 may be of varying sizes as best suited for the work involved, and said gear is adapted to mesh with a gear 118, suitably secured on a stub shaft 119, which projects into the block 102 and has bearing therein, said shaft 119 being driven or rotated through the medium of a flexible or universal coupling, generally indicated at 120, from a drive pinion or gear 121, see Figs. 1 and 2, which is suitably secured on a further stub shaft 121^a having bearing in an extension of the bracket 91. The coupling 120 includes a sleeve 120^a and stub 120^b in spline-sliding engagement therewith, so that the coupling may automatically extend itself during shifting action. A lever 122, formed with a toothed sector 122^a, is adjustably and pivotally secured as in Figs. 5 and 6 to a further extension of the bracket 91, as at 123, said lever being provided with a cam roller adapted to contact with a cam 124, preferably adjustably secured as in Figs. 9 and 10 on the shaft 79. A spring 125 connects at opposite extremities, respectively, to the lever 122 and bracket 91, to retract said lever when actuated by cam 124. This cam and lever assembly is substantially similar to that shown at the lower portion of Fig. 1 and hereinbefore described, and likewise, the cam 124 may be substituted by different shapes of cams adapted for the work involved.

55 The shaping head assembly is preferably pivotally supported from the lower horizontally sliding bar 69, the block 102 being formed or cast with a stub shaft 126, see Fig. 2, having a gear 127 suitably secured thereon, the said shaft 126 having bearing in a bracket 128, which is secured to the bar 69 as by screws 128^a. The shaft 126 is prevented from displacement by a collar 126^a secured as by a screw or the like on said shaft. To tilt or rock the head 92, an angle lever 129, see Fig. 1, is adjustably fulcrumed as in Figs. 5 and 6 at 130 on the supplemental frame unit 66, the one extremity of said lever

being pivotally and adjustably connected to the cam-contacting bracket 81 as by a turn-buckle 131, a plurality of securing holes being provided in said lever and said bracket so as to permit adjustment of the position of 70 said turn-buckle thereon, and the opposite extremity of said lever is provided with a pin or analogous member 132, adapted to engage in a slot 133 formed in a T-head 134, which may be cast or formed on the upper 75 extremity of a rack 135, the latter extending down and being adapted to mesh with the gear 127 secured on the stub shaft 126 of block 102, a suitable retaining and guide bracket 136 being provided which may be 80 cast integral with or be secured to the bracket 128 on the slide bar 69.

It will be seen that when cam 84, in contact with bracket 81 on slide bar 80, rotates, it will actuate lever 129 fulcrumed on the 85 vertically slidable frame unit 66, said lever in turn actuating rack 135 in mesh with gear 127, to thereby tilt the head 92, this tilting action being under ready control and adjustable while in operation as to phase, by adjusting cam 84, extent or degree, by adjusting fulcrum point 130, and angular position by adjusting turn-buckle 131, and through the medium of the cam 90 acting on lever 85 to reciprocate the frame unit 66, the head may be 90 reciprocated vertically, the phase and extent and altitude of vertical reciprocation being also under ready control while the apparatus is in operation by adjusting cam 90 and/or pivot point 89 of lever 85, and during this tilting and reciprocating action the head may be 95 rotated through the medium of cam 124 acting on lever 122 to rotate gear 121, the drive being transmitted to head 92 through the medium of flexible coupling 120 and gears 118 and 100 103, the phase of rotation being under ready control by adjusting cam 124 while in operation and while the driving connection subsists, and by varying the pivotal connections 105 59 and 123, the speed and extent of rotation 110 of the chuck 13 and/or head 92 may be varied and adjusted while in operation or while performing their respective functions. The shafts 79 and 64 are preferably driven in synchronism, so that during reciprocation 115 and rotation of the head 92, the chuck 13 with the mold A and ware thereon may be given any desired relative rotation and reciprocation in accordance with the work involved. As heretofore specified, any number 120 of different styles and shapes of cams may be provided, those herein shown being simply to illustrate the adaptability of the apparatus to the method.

Means are provided for automatically supplying the surface of the formed or partly formed ware with a suitable coating of material in synchronism with, and during operation thereon by the head 92, one form of said means being herein illustrated as a pug-mill 125 130

assembly comprising a horizontally-disposed container 138 provided with a bracket plate 139, by which it may be suitably secured to a main supporting bracket 140, the latter depending from and being suitably secured to the platform or plate 5^a. The container 138 is provided with a feed screw 141, the shaft of which has bearing in an end cover plate 142, which may be bolted or otherwise secured to the container 138 and provided with a bearing bushing for said shaft, a gear 143 being secured on the projecting extremity of the feed screw shaft as by a screw 143^a and adapted to mesh with a rack 144, which is pivotally secured at one extremity to a lever 145, the latter being adjustably pivoted as at 146 preferably as in Figs. 5 and 6, the adjustment assembly being supported from a bracket 147, which may be suitably secured to the platform or frame plate 5^a. The rack 144 is guided and prevented from displacement by a guide bracket 148, which may be secured to or cast integral with the cover plate 142 of the container 138, the rack being provided with teeth which intermittently mesh with said gear 143 to rotate the latter in one direction, said rack being maintained in contact with the gear by a compression spring 148^a, see Fig. 3. At an intermediate point the lever 145 is provided with a cam roller 145^a, adapted to have movement in the groove or track of a cam 149, which is preferably adjustably secured as in Figs. 7 and 8 on a shaft 150, which may have bearing at opposite sides of the main frame of the apparatus and also in the supporting bracket 140. The container 138 is provided with a hopper 151 and an outlet orifice 152, and to regulate the pressure of the material at the orifice extremity of the container, the wall of the latter is formed with a longitudinal chamber 153 having a valve-controlled inlet 154 and terminating at its outlet extremity in the hopper 151. The inlet 154 to the chamber 153 is shaped to seat a valve generally indicated at 155, said valve being normally seated in the inlet 154 and retracted from seated position against the pressure of a suitable compressing spring, the latter being adjustable through the medium of an adjustable bushing or sleeve 156, adapted to receive the valve stem and provided with an adjusting and set nut or analogous member 157, see Fig. 3. By adjusting the tension of said spring, the inlet 154 may be controlled so as to permit the material in the container to pass therethrough and into the chamber 153 under a predetermined maximum pressure, the material passing back into the hopper 151.

As the material is extruded through the orifice 152 of the pug-mill or container 138, it is segregated into charges, and with this end in view a wire, knife or analogous member 158, see Fig. 3, is mounted in the yoke extremity of a cutter bar 159, the latter being pivotally secured to the one extremity of a lever 160, the opposite extremity of said lever being adjustably pivoted at 161, the pivoting assembly preferably being in the form shown by Figs. 5 and 6 and supported from a bracket 162, which is secured to the platform or frame plate 5^a. The lever 160 is provided with a cam roller 160^a, adapted to contact with a cam 163, which is adjustably mounted as in Figs. 7 and 8 on the shaft 150. The orifice extremity of the container 138 may be formed with, or have secured thereto a guide bracket 164, which is formed with guide grooves 164^a, see Fig. 3, adapted to receive the bracket extremity of the cutter bar 159 and also an orifice regulating slide or gate valve 165, which is formed on one extremity of a bar 165^a and provided with a turn-buckle 165^b to adjust its position, the said bar 165^a being pivotally secured to the one extremity of a lever 166, formed with a fulcrum slot 167 and fulcrumed at 168 preferably as in Figs. 5 and 6, the assembly being adjustably supported from a bracket 169 which is secured to the platform or frame plate 5^a, said bracket being of angle construction and provided with a plurality of threaded holes 170, see Fig. 3, to receive the supporting bar 168^a for the fulcruming assembly.

As the material is segregated in suitable charges, it is conveyed to the hopper portion 106 of the chamber, well or orifice 105 of the head 92 through the medium of a chute 171, which is pivotally secured at one extremity as at 172 to an upright or standard 173, which may form part of, or be secured to the block 102, and at its opposite extremity said chute is adjustably and movably supported by a bracket 174, the latter being cast integral with or suitably secured to the container 138 and formed in sections and connected by a coupling or union 175, the lower extremity of the bracket being provided with a roller 176, adapted to movably support a guide rail 177, the latter being cast integral with or forming part of the chute 171.

The material may be applied by pressure over the surface of the ware by a plunger 178, adapted to work in a cylinder 179, said plunger being provided with a piston 180 at an intermediate point and a stem 181, the latter having a sliding fit in the upper end of the cylinder and threaded to receive a contact collar or nut 182, adapted to contact with the one extremity of the valve-regulating lever 166, and the cutter bar 159 is also provided with a contact member or pin 183 adapted to contact with the opposite extremity of lever 166. The cylinder 179 may be bolted or otherwise secured to a bracket 179^a, which in turn is secured to the block 102, said bracket also serving to stabilize the stub shaft 119. The plunger 178 is preferably actuated by air under control of a preferred type of valve which will presently be described and regu-

lated so that if an excess amount of material is delivered into the chamber or well 105, only the required amount will be pressed out over the surface of the ware, the plunger only being depressed a certain distance into said chamber due to excess material preventing further descent. Thus, by adjusting the contact nut 182 on stem 181 so that it will contact with and actuate lever 166 to raise valve 165 such distance as will reduce the orifice 152 of container 138 to a predetermined extent, a correspondingly reduced charge will be extruded from the container, and as the cutter bar 159 lowers, contact pin 183, which may be adjusted to a predetermined position, again actuates lever 166 which lowers the valve to its original position, so that by properly adjusting contact members 182 and 183, the charges of material may be automatically 20 equalized. The cylinder 179 is provided with nipples 184 and 185, adapted for connection of hose or other flexible members leading to the control valve above referred to and hereinafter described.

25 Where the material is in such fluid or plastic state as may not be suitable for the pug-mill assembly just described, the charge applying and measuring device illustrated in Fig. 13 and generally indicated by the reference numeral 186 may be used. This device may be adjustably supported from the platform or frame plate 5^a by a bracket 187, the lower extremity of the latter being of angle shape and bored to receive an externally threaded sleeve 188, the latter being adjustably secured as by adjusting and securing nuts 189, the lower extremity of said sleeve terminating in an externally and internally threaded head adapted to be threaded into the 30 charger casing 190, which is internally threaded at the upper portion thereof, said casing being provided with an inlet port 191 and outlet port 192, controlled by check valves or analogous means, the port 191 having a hose or other flexible member 191^a connected thereto and leading to a source of supply such as a slip tank or the like, not shown, and the port 192 having a similar member 192^a connected thereto and leading to the 35 chamber or well 105 and/or nipples 109 and 110 of the head 92, or to any other point of application of the material. A further port 193, also controlled by a check valve, is formed in the casing 190, said port having a 40 hose or other suitable flexible member 193^a connected thereto and leading to a source of deposit of slip that may seep past the plunger 194 of the device. The plunger 194 is provided with a stem 194^a having a sliding fit 45 in the sleeve 188, the upper extremity of said stem projecting through the platform or frame plate 5^a, a suitable compression spring 195 being disposed around said stem and bearing at opposite ends respectively against 50 said plate and a collar 196, which is adjust-

ably secured on said stem to adjust the tension of spring 195. The piston 194 and sleeve 188 may be provided with packing and packing gland to prevent leakage.

To reciprocate the plunger 194, a lever 197 is adjustably fulcrumed at one extremity as at 198 on a bracket 199, see Fig. 3, which may as usual be secured to the platform or frame plate 5^a, the manner of fulcruming said lever preferably being as shown in detail in Figs. 5 and 6, and at its opposite extremity said lever is formed as a fork or yoke and pivotally connected to a pivot block 200, the latter being adjustably secured on the plunger stem 194 as by screws 200^a. The lever 197 is provided with a cam roller 197^a adapted to contact with a cam 201, see Fig. 3, the latter being adjustably mounted preferably as in Figs. 7 and 8 on the shaft 150, the spring 195 serving to maintain the cam roller 197^a in contact with cam 201 and apply regulable pressure and variable travel to the piston 194, and as the fulcrum point 198 of lever 197 may be shifted while in operation and the angular position of cam 201 also varied while in operation, the reciprocation and phase of reciprocation of said plunger 194 may be likewise varied, to thereby measure the charges of material and time of application of the same while the device is operating to deliver said charges. To provide for automatic equalization of the charges as in the pug-mill assembly, the lever 197 is formed with a toothed portion 202, an adjustable length contact pin 203 being adjustably secured as by screw 203^a, see Fig. 3, on a supporting shaft or bar 204, the latter being rotatably mounted in a journal bracket 204^a which is suitably secured to the one extremity of bracket 187, and at a point adjacent to or above the lever 166 an arm 205 is adjustably secured thereon as by screw 205^a, an adjustable-length connecting rod 206 being pivoted at one extremity on said arm and at its opposite extremity pivotally connected to the lever 166, see Fig. 1. In operation, the contact collar or nut 182 of stem 181 may be given a predetermined adjustment to contact with lever 166 at each stroke of piston 180, thus rotating shaft 204 and swinging the point or edge of contact pin 203 varying distances to engage the toothed portion 202 of lever 197 at varying points, depending upon the lowermost point reached by contact collar or nut 182 and which is governed by the size of the charge. Thus if a charge is abnormally heavy, the piston will only descend to a certain point and nut or collar 182 will give a correspondingly limited actuation to lever 166 and arcuate swinging movement to pin 203, which will accordingly limit the succeeding stroke of lever 197. To return the lever 166 to its normal working position preparatory to a succeeding stroke, the lever 160 bearing the contact pin 183 may re-

main connected up to operate as in the pug-mill assembly.

Figs. 11 and 12 illustrate a valve structure and actuating means therefor adapted for controlling the application of a fluid medium, including super and/or sub-atmosphere to such parts of the apparatus as may be desirable. The valve herein shown comprises a casing 207, which may be adjustably supported from a part of the frame of the apparatus as by inserting suitable fastening devices in enlarged openings 208 or by a thread bolt 209, threaded at one extremity into said casing and at its opposite extremity extending through an enlarged opening and adjustably secured as by nuts 210, a chamber 211 being provided in the casing, a plunger 212 being mounted to reciprocate in said chamber and provided with ports 213 and 214, said casing also having formed therein ports 215, 216 and 217, which are enlarged and interiorly threaded to receive nipples for connection of suitable flexible members or hose 218, 219 and 220. The plunger is formed as a bracket at one extremity, as at 221, slotted or cast with an open portion as at 222, to enable application over an actuating shaft which in this instance may be the shaft 150 or the shaft 55, the shaft in Figs. 11 and 12 being indicated as 150, cam-contact members or pins 223 and 224 being secured in or cast integral with said bracket and projecting at right angles therefrom, said pins being adapted to contact with cams 225, 226, 227 and 228 which serve to control complete and intermediate shifting of the plunger in both directions, said cams being preferably adjustably mounted as in Figs. 9 and 10. Ordinarily frictional contact will serve to maintain the plunger 212 in shifted position, but to balance the weight of said plunger and ensure its remaining in shifted position, the one extremity thereof is notched as at 229 and the casing bored and threaded to house a resiliently mounted registering assembly or detent structure shown in the form of a ball 230, spring 231 and screw 232, the notches 229 being spaced in accordance with the shifting movement of plunger 212. Thus when the plunger reaches its approximate shifted position, the ball 230 will engage in one of the notches 229 and releasably hold the plunger in shifted position. As each cam is so mounted as to permit adjustment thereof while in operation, the plunger may be timed and given varying dwell periods and degrees of shift while the valve is functioning, to thus time and regulate the dwell of application of the fluid medium. Any number of these valves may be provided, the flexible members or hose 218 and 220 leading to a source of supply of super and sub-atmosphere or other medium, or one of said members may lead simply to the atmosphere, and the flexible

member or hose 219 leading to the point of application or introduction of the medium.

The spindles 11 are provided with longitudinal bores 11^a, see Fig. 1, the spindles 12 being hollow, thus providing a passageway 70 as at 12^a registering with the bore 11^a which terminates at its lower extremity in a nipple-attaching portion 11^b. The chucks 13 are shown as being threaded on the spindles 12, see Fig. 14, and bored to provide a passageway 12^b registering with passageway 12^a and opening out in the top of the chuck at the central and other portions of the latter, the central opening being closed by a screw plug 12^c and the chuck being formed with a further bore or passageway 12^d leading to the atmosphere, for a purpose which will be hereinafter apparent. While the usual type of plaster mold may be used to advantage in the present apparatus, it is preferred to use the form of mold shown in section in Fig. 14 and comprising a body or clay-receiving portion *a* of porous material such as plaster, and a metal base *b* the body and base portions being detachably associated as by a ring *c*, chambers *e* and *f* being formed in the mold, and when the mold is seated on the chuck, these chambers are sealed, the chucks preferably being provided with suitable sealing means such as a flexible peripheral valve 12^e and embedded rings 12^f which also serve as cushioning means.

It will be seen that when the mold is seated on the chuck, a sub or super-atmospheric condition may be created in the chambers *e* and *f* and which is communicated to the surface of the mold and the clay or ware that may be disposed thereon through the porous body *a* of the mold, or selectively as by providing vents *g* in the mold or body portion *a* thereof. The passageway or bore 12^d provides independent control of the chamber *e*, and the plug 12^c may be used to selectively close the passageways leading to the chambers *e* and *f*, it being obvious that any number of these plugs may be provided.

It may be desirable in some instances to apply air under pressure to the under portion of the molds to such an extent as will require additional means other than the force of gravity or weight of the molds and ware to maintain the molds in stable position on the chucks, in which event the chuck may be provided with a coil as at 232 and the spindles 11 with commutators adapted to make intermittent contact with brushes which may be supported from the frame units 9. A suitable switch generally indicated at S in Fig. 11 may be associated with the plunger bracket 221, and through the medium of which the chuck may be magnetized and de-magnetized during reciprocation of the chuck, to attract and repel the mold relatively to the chuck. For a more complete description of this magnet and

switch structure, reference is made to my co-pending application Serial No. 275,395, filed May 5, 1928.

The shafts 64, 79 and 150 are preferably provided with sprockets or analogous members and connected by a suitable positive flexible driving member as indicated at 233 and driven in synchronism.

At the right of Fig. 1 a fragment of a treating member or nozzle 234 is shown, to indicate that the ware may be treated by applying a suitable fluid or other medium thereto prior to being operated upon by the apparatus.

For an example of one of the numerous operations of which the apparatus is capable, let it be assumed that a layer or coating of clay is to be applied to the under portion of a series of plates subsequent to being jiggered, this extra layer of clay to be of a different color than the face of the plate and to have a scalloped effect. The contour or shape of cams 63 and 124 and also cams 78, 84 and 90 as shown in Figs. 1 and 1^a would be suitable for this operation, cams 63 and 124 serving to impart intermittent relative rotation to the mold A and head 92 while the cam 90 reciprocates the head vertically and cam 84 tilts the said head at a suitable angle during this intermittent rotation and reciprocation. In this instance a comparatively stiff clay suitable for the pug-mill assembly could be used. As the molds with the freshly jiggered ware are conveyed adjacent the treating nozzle 234, a suitable fluid or other medium may be applied to the ware preparatory to the decorating operation. When the tray bearing the molds with the ware thereon moves over and registers with the chucks 13, the latter rise and elevate the molds clear of the trays and the heads 92 may at the same time be lowered, the heads substantially encompassing the molds and both the molds and heads being intermittently rotated in synchronism. A charge or batch of clay of suitable size in accordance with predetermined adjustments may be discharged from the pug mill onto the chute 171 and from thence pass into the well or chamber 105, the plunger 178 then descending and forcing the clay over the surface of the ware, the relatively intermittently rotating mold and reciprocating and angularly tilting head pressing, kneading and smoothing the extra layer of clay onto the ware, and if desired, the angular tilt of the head may be adjusted so as to give a scalloping effect to the layer, and this effect may be enhanced by adjusting the angle to the point where the head presses the extra layer clear of the ware at regular spaced distances so that the depressions or flutes expose the tint or color of the ware beneath the layer. During the decorating operation the treating members 99 may be utilized for any purpose

to which they may be adapted, as for applying a lubricant, coloring fluid, powder, etc., and these members may also be adjusted so as to protrude from or recede into the facing 93 and form indentations or protrusions or designs in or on the ware. If the clay has a tendency to adhere to the facing 93, air under pressure may be applied to the chambers 98 and through the porous facing, and also through the members 99 if the latter be used, to the clay, the valve 207 providing complete control of both sub and super-atmosphere as well as other fluid mediums to be applied to the ware through the head 92 and mold A through chuck spindles 11 and 12 and chuck 13, and heat may also be applied through the medium of coil 111. In many instances only a pressing or stamping action may be required, as where the facing 93 has a design or trade-mark name embossed or engraved therein, in which event cam 90 may have a regular or smooth contour and the remaining cams 63, 124 and 84 disconnected, or it may be desired to simply rotate the head and not the mold or rotate both in opposite directions, the apparatus being capable of practically any desired relative reciprocatory, rotative and angular movement of the head 92 and mold A by simple and obvious modifications in the contours of the cams and proper adjustment of the parts.

Fig. 20 illustrates diagrammatically a number of the relative operating positions of the head 92 and mold A. At B the head 92 is shown working in vertical concentric alinement with the mold, and this may simply be a pressing action or a rotating and kneading action or rotating and reciprocating action, as will be obvious in view of the foregoing description. At C the head and mold are shown working in the same horizontal plane but out of vertical alinement. At D the head is shown working at an angle or tilted and in concentric rotary relation with the mold. At E the head is also working at an angle but in eccentric rotary relation with the mold. At F the head is shown working at substantially right angles relatively to the mold. Various combinations of the foregoing working positions may be effected, and as the various working parts may be adjusted while in operation, these working positions may also be varied while the head is working on the mold. Thus the apparatus is rendered adaptable for various forms of decorative and design work and in accordance with the particular attachment or form of head 92 in use, the latter being capable of rotative or angular, tilting, horizontal and vertical motion, or in other words, universal motion.

Fig. 14 illustrates an example of how the shape of ware may be changed after jiggering without involving the use of complicated jiggering apparatus. In this instance the

working surface of the facing 93 is given the shape it is desired to give to the ware, as by forming a series of indentations as at 235, or a design or ornamental figure. If it is desired to have the design or indentation shown on both sides of the plate, or be concavo-convex, the facing 93 only need be designed or indented as at 235, while if the design or indentation is to show on one side only of the ware, then the mold should be formed with cooperating designs or indentations as at 236, the clay being originally smoothed or pressed thereinto by the profile. The vents ^g in the mold may be formed at such points as it is desired to concentrate the force of the air under pressure or super-atmosphere, and likewise the facing 93 may be formed with vents to concentrate the application of sub-atmosphere, or vice versa. When the head 92 contacts with the mold having the freshly jiggered ware thereon, air under pressure may be applied to the mold, to conform the soft ware to the shape of the working surface of the facing 93 and, if necessary, sub-atmosphere pressure may be applied to the facing 93 to assist in this operation. It will be noted that the ware is practically enclosed on all sides by the facing and mold. The plugs 12^c may be utilized, by providing any number thereof and interchanging their positions, to concentrate the super and/or sub-atmosphere in either of the chambers *e* or *f* of the mold, and if the force of the air under pressure should have a tendency to displace the mold on the chuck, the switch *S* may be rendered operative to magnetize the chuck and attract the metal base *b* of the mold. In this instance the chamber or orifice 105 may be dispensed with, the component parts of the head 92 being indicated by like reference numerals but slightly modified to adapt the head to the foregoing operations. Agglutinants may be added to the clay mixture to condition the latter when producing ware by the foregoing method.

In some instances it may be desired to decorate or otherwise treat the ware as by printing, stamping, sponging, ground laying, dusting, etc., before firing, and in Fig. 15 an attachment particularly adapted for this purpose is illustrated. The facing 93 may be comprised of suitable material in accordance with the work involved, as for instance rubber, felt, sponge, etc., and supplied with the required coloring fluid, oil and the like through the medium of the member diagrammatically illustrated at 237, which may be in the form of a stamp pad, platen and the like and adjustably supported from a bracket 238. In the instance shown the pad member 237 is provided with a plurality of chambers 239 and hose-attaching nipples 240 communicating with said chambers, to illustrate how, in stamping for instance, a suitable coloring fluid or fluids may be supplied to the

chambers 239 and exude to the surface of the pad. A nozzle member 241 having a plurality of supply branches is also illustrated, to indicate how the facing 93 may be sprayed or otherwise treated by application of a fluid or combination of fluids or other mediums. In operation, the head 92 may be actuated to alternately move the facing 93 against the pad or other member 237 and the ware, and during the arcuate movement of the head past the nozzle 241, a suitable spray of fluid, dust or the like may be applied to the facing before or after being pressed against the pad 237, the dotted position showing the head 92 against the pad, or in some instances only the nozzle may be necessary to apply the fluid or other medium to the facing 93 while in others only the member 237 may be required. The member 237 may be formed with designs of absorbent material in relief, as a ring or star, the design, name or other marking being applied to the facing and then to the ware. Any desired medium may be applied to the facing 93 through the ports 107 and 108 or orifice 105 in cooperation with the members 241 and 237.

Incrustations may be applied to the ware by sinking or otherwise forming a design in the members 99, filling the design with clay or other material by moving the facing 93 bearing said members against the pad 237, holding the clay or other material in the design, if necessary, by sub-atmosphere, then moving the facing against the ware to apply the design or incrustation, and finally releasing the clay or other material by super-atmosphere or air under pressure. The material may also be applied to the members 99 through the nozzle 241 or treated during movement past said nozzle.

In Fig. 16 the attachment is particularly adapted for decorating the interior of deep ware, a plurality of resiliently mounted decorating or stamping members or tools 237^a being provided. In this instance the assembly ¹¹⁰ comprises a main support or cross-head 242, slotted as at 242^a, brackets 243 also slotted at 243^a, cylinders 244, pistons 245, springs 246 and nuts or bushings 246^a, the members or tools 237^a being secured on the stems of the pistons 245. The cross head 242 is threaded on the holder 100 and the brackets 243 adjustably secured to the cross head by securing bolts passed through the slots 242^a and 243^a, the cylinders 244 being adjustably secured to said brackets and the pistons mounted to have a sliding fit in said cylinders against the pressure of said springs. The cylinders are provided with air vents or exhaust ports 247 shown formed in the nut or bushing 246^a, and air inlet ports 248, the latter having hose or analogous flexible members 248^a connected thereto and leading to the duct or passage 107, which in this instance is formed in the bushing or sleeve 100 and cross head 242. ¹²⁰

The members 237^a are chambered as at 249, said chambers communicating with the working surfaces of said members through ducts 249^a and also having hose or analogous flexible members 249^b connected thereto and communicating with the duct 108, which in this instance, also, is formed in the holder 100 and cross head 242.

In operation, the decorating fluid or other material may be supplied to the members or tools 237^a through the port or duct 108, and in order that the said members may be moved into and out of contact with the surface of the ware at substantially right angles relatively thereto, the valve shown in Figs. 11 and 12 may be connected up with the port or duct 107 and timed so as to admit air under pressure to the cylinders 244 through ports 248 when it is desired to retract the members 237^a from the surface of the ware. The springs 246 apply pressure to the members or tools 237^a and this pressure is adjustable through the medium of the threaded nuts or bushings 246^a. To adjustably limit the maximum degree of extension of the members 237^a, the cylinder head is adjustably secured or threaded into the cylinder 244. Angular movement of the members 237^a is prevented by pins 245^a.

With this attachment the interior of deep ware may be decorated in various ways, as by applying colored patterns or designs in spaced relation around the interior side walls of the ware by reciprocating said members during rotation of the cross head 242, or said members may simply be moved into contact with the surface of the ware and the head 242 rotated, to coat the whole interior surface or form an annular ring or some similar design.

Fig. 17 shows how an engraving or turning tool attachment may be applied to the apparatus, the tool, indicated at 250, being motor-driven in the instance shown, the motor 251 being adjustably secured to an attaching head 252, which may be threaded or otherwise secured on the holder 100. The motor may be supplied with current through the medium of annular commutators 253, mounted on said head 252, and brushes 254, which are mounted on a non-rotating bracket ring 255, interposed between the gear 103 and a collar 256 on the holder 100.

Various designs may be engraved in the ware, which may be in a soft, leather-hard or completely dried state, the head 252 being adapted to be rotated, reciprocated and tilted angularly, providing a means for guiding the tool as desired. Any form of tool may be used, as for instance an abrasive tool for smoothing dried ware or cutting off projections or stubs and which is usually done by manual labor.

In Fig. 18 an attachment adapted for shaping the interior of deep or undercut ware is

illustrated and in the present instance is shown making an insulator. A former or shaper 93^a, preferably of porous material, is provided and formed with a threaded socket 257 for application to the holder 100, said former in the instance shown terminating in an exteriorly-threaded flared insulator-shaping head 258. The orifice or central passage 105 in this form of attachment may have a removable plug 259 applied to its lower extremity during certain shaping operations, as in making insulators, and super and sub-atmosphere as well as other fluid mediums may be applied through the orifice or passage 105 as well as through the ducts or passages 107 and 108.

In making insulators the clay may be simply fed or dropped into the molds in suitable sized batches, and when the molds are advanced adjacent or under the apparatus, the shaper may be lowered into the mold and rotated at an angle and eccentrically relatively to the vertical axis of the mold, the latter being rotated in the same direction, the clay being pressed against the sides of the mold as in the ordinary jiggering operation, or the clay may be preshaped or jiggered prior to being operated on by the shaper. After the insulator has been formed or shaped, the shaper 93^a may be moved toward the center of the insulator sufficiently to clear the threads and/or undercut portion and the mold lowered or the shaper elevated to clear the insulator. Should the clay have a tendency to adhere to the shaper, a suitable fluid medium may be applied through the passages 107 or 108 or orifice or well 105, the fluid passing through the porous material of the shaper and providing a film between the shaper and clay which prevents adhesion of clay to the shaper. The mold A in this instance may be of the portable type, a clamping ring 260 being applied therearound.

Fig. 19 illustrates a modified form of actuating mechanism for the head 92. The lever 129 in this instance is straight instead of angle shape and pivoted to a rack 261, which is guided and prevented from displacement by guide brackets 262 and 263 secured to the frame 66. A pinion or idler gear 264 is rotatably mounted on a stub shaft 264^a secured in the horizontally sliding bar 69, said gear meshing with the rack 261 and a floating rack 265, which is guided and prevented from displacement by guide brackets 266 and 267 secured to the bar 69. A speed-reduction unit comprising gears 268 and 269 is rotatably mounted on a stub shaft 270 secured in the frame 66, the rack 265 meshing with gear 268, to thereby transmit motion to a further floating rack 135^a in mesh with gear 269, said rack 135^a being guided and prevented from displacement by the bracket 266 and a further bracket 272, also secured to the bar 69, the rack 135^a meshing with gear 127 and the

latter being pivotally supported from bar 69 substantially as in the prior structures heretofore described.

In operation, the head 92 is moved vertically with the frame 66 and laterally with the bar 69, while at any time during its vertical and lateral movements, said head may be given an angular or tilting movement through cam 84 and the rack and pinion assembly just described, movement of rack 261 toward the right, for instance, as viewed in Fig. 19 moving rack 265 toward the left, which through gears 268 and 269 also moves rack 135^a toward the left, tilting head 92 at an angle. Through the medium of the speed-reduction gears 268 and 269, the rack 135^a moves at the same speed as the bar 69, so that the desired tilted position of the head 92, resulting primarily from cam 84, is maintained regardless of the movement of said bar.

What is claimed as new is:

1. In a machine of the class specified, the combination with a mold adapted for an article of pottery ware, of a source of supply of additional material, and means for automatically applying the said material in measured quantities to the surface of the ware while the latter is in a plastic state and shaping the material on said surface.

2. In a machine of the class specified, the combination with a mold adapted for an article of pottery ware, of a source of supply of additional material, means for automatically applying said material in measured quantities to the surface of the ware, and a shaping member having universal movement adapted to selectively distribute the material over said surface.

4. In a machine of the class specified, the combination with a mold adapted for an article of pottery, of a source of supply of additional material, a kneading and shaping member adapted to operate relatively to the surface of the ware, and means for applying the material in measured quantities to said surface through, and during operation of said member.

5. In a machine of the class specified, the combination with a mold adapted for an article of pottery ware, of a source of supply of additional material, a movably mounted distributing and shaping head, means for automatically applying the material in measured quantities to the surface of the ware, and means for relatively reciprocating and rotating said head and (or) said mold to distribute and shape said material over said surface.

6. In a machine of the class specified, the combination with a mold adapted for an article of pottery ware, of a source of supply of additional material, a distributing and shaping head mounted for universal movement relatively to the ware, means for automatically applying the material in measured

quantities to the surface of the ware, means for relatively moving said head and (or) said mold to distribute and shape the material, said movement being variable during the distributing and shaping operation.

70 6. In a machine of the class specified, the combination with a support adapted for ware, of a source of supply of additional material, and means for automatically segregating the material in measured charges and conveying the charges to the ware.

75 7. In a machine of the class specified, the combination with a support adapted for ware, of a source of supply of additional material, means for automatically segregating the material in measured charges and conveying the charges to the ware, the quantity of material comprised in a charge being governed by the quantity of material comprised in the preceding charge.

80 8. In a machine of the class specified, the combination with a support adapted for ware, of a source of supply of additional material, means for automatically segregating the material in measured charges and delivering the charges to the ware, the phase of segregation and delivery being variable while the charges are being segregated and delivered.

85 9. Apparatus for slip-glazing and decorating ware in the manufacture of pottery, comprising in combination, a support adapted for the ware and a universally movable member having a ware-contacting surface provided with ware-decorating instrumentalities which project and/or recede from said surface.

90 10. Apparatus for slip-glazing and decorating ware in the manufacture of pottery, comprising in combination, a support for the ware, a universally movable member having a ware-contacting surface provided with the design desired to be applied to the ware, and means for automatically applying a suitable glazing and decorating medium to said surface.

10 11. Apparatus for reshaping and decorating ware in the manufacture of pottery, comprising in combination, a support for the ware, and a shaping and decorating member having a ware-contacting surface of porous material to provide for the application of a fluid medium to the ware through said member.

11 12. Apparatus for reshaping and decorating ware in the manufacture of pottery, comprising in combination, a support for the ware, a shaping and decorating member having a chambered body and a ware-contacting surface provided with treating and decorating members, means for applying additional material and a treating medium to the surface of the ware, and means for imparting universal movement to said member to coat the surface of the ware with said material and simultaneously decorate and design the ware.

13. Apparatus for reshaping and decorating ware in the manufacture of pottery, comprising in combination, a support for the ware, a reshaping and decorating member adapted to operate relatively to the surface of the ware, and means for exerting a super and (or) sub-atmospheric influence on the ware through said member. 70
14. Apparatus for reshaping and decorating ware while in a plastic state in the manufacture of pottery, comprising in combination, a mold adapted for the ware, a reshaping member adapted to contact with the surface of the ware, the ware-contacting surface of said member being shaped in accordance with the desired shape of the finished ware, and means for exerting a sub and (or) super-atmospheric influence on the ware to cause it to conform to the ware-contacting surface 75 of said member.
15. The method of decorating pottery ware, which consists in applying a measured quantity of additional material to the ware while in a plastic state, kneading and shaping the said material over the surface of the ware to form a bond therebetween, and subjecting the ware to the drying operation. 80
16. The method of decorating pottery ware, which consists in applying a measured quantity of additional material to the ware while in a plastic state through a movable distributing and shaping member having a porous working surface, imparting relative movement to said member and the ware to distribute and shape the material over the surface of the ware, applying a fluid medium to the material through the said porous working surface to facilitate the decorating operation, and subsequently drying the ware. 85
17. In the manufacture of pottery ware, the method which consists in initially applying a clay blank to a molding surface, disposing a former member adjacent the blank while in a plastic state, and applying pressure on the blank through the molding surface to transfer the contour of the molding surface in whole or in part to the opposite surface of the ware. 90
18. The method of decorating and reshaping jiggered pottery ware while on the mold, which consists in providing a former member having a ware-contacting surface shaped in accordance with the design or shape to be given the ware, encompassing the ware while in a plastic state by the former member and mold, and exerting abnormal atmospheric pressure on the ware to conform the ware to the surface of said member. 95
19. Apparatus for reshaping and decorating ware in the manufacture of pottery, comprising in combination, a support for the ware, a decorating and shaping head provided with ware-decorating members adjustable to protrude or recede from said head, and means for applying additional material 100 to said members and transferring said material to the ware in the form of decorating incrustations.
20. In a machine for reshaping and decorating ware in the manufacture of pottery, a holder adapted for the application thereto of attachments in accordance with the work involved and means for universally positioning said attachments with respect to the work. 105
21. In a machine of the class specified, the combination with a mold adapted to support ware, of a source of supply of material, a distributing and shaping head mounted for movement relatively to the ware, means for automatically applying the material in measured charges to the surface of the ware, and means for reciprocating said head and/or said mold to shape the material. 110
22. In a machine of the class specified, a holder adapted for the application thereto of attachments in accordance with the work involved, means for imparting universal motion to said holder and means for varying the phase and degree of said motion. 115
23. In a machine for decorating ware in the manufacture of pottery, the combination with a mold adapted to support the ware, of a shaping member adapted to rotate at an angle relatively to the ware during operation thereon, and means for varying the degree of angularity during rotation of said member. 120
24. In a machine for decorating ware in the manufacture of pottery, the combination with a mold adapted to support the ware, of a shaping member adapted to operate in an eccentric vertical plane relatively to the mold, and means for varying the degree of eccentricity while said member is operating on the ware. 125
25. In a machine of the class specified, the combination with a mold, of a distributing and shaping head, means for intermittently relatively reciprocating and rotating said head and/or said mold, said means being adjustable while in operation to vary the reciprocatory and rotative movement. 130
26. In a machine for decorating ware in the manufacture of pottery, the combination with a mold adapted to support the ware, of a shaping and decorating member, means for imparting relative rotation to said member and/or said mold, and means for varying the speed of such rotation during the shaping and decoration operation. 135
27. In a machine for reshaping and decorating ware in the manufacture of pottery, the combination with a support for the ware, of a source of supply of additional material, means for automatically segregating the material in measured charges and delivering the charges to the ware, and means for varying the charge during segregation and delivery thereof. 140
28. Apparatus for slip-glazing and deco- 145
